INVENTOR

HOMER H. INGERSOLL,
by Oscar A. Michel ATTORNEY

UNITED STATES PATENT OFFICE.

HOMER H. INGERSOLL, OF ST. LOUIS, MISSOURI.

UPHOLSTERING MACHINE.

Application filed January 18, 1922. Serial No. 530,021.

To all whom it may concern:

Be it known that I, HOMER H. INGERSOLL, a citizen of the United States, residing at St. Louis, State of Missouri, have invented 5 new and useful Improvements in Upholstering Machines, of which the following is a specification, reference being had to the accompanying drawings.

My invention relates to improvements in 10 upholstering machines particularly designed for use in the manufacture of cushions for chairs, settees, and like furniture as well as mattresses for beds, cots and the like.

The object of my invention is to provide 15 a machine comprising relatively movable elements in which the cushion filler comprising a body of coil wire springs or hair, or excelsior or other equivalent and a pad of felt, cotton or the like is built up, manually, after which the recited elements are automatically operated to size the built-up filler and insert it bodily into a casing or cover.

My improvements consist in the novel 20 construction, arrangement and combination 25 of parts as hereinafter fully, clearly and concisely described, definitely pointed out in my claims and illustrated by the accompanying drawings, (four sheets) in which:—

Figure 1 is a side elevation of the machine, with parts broken away, showing the 30 vertical sizing element, or press, by dotted lines in an elevated or open position.

Figure 2 is a plan view of the machine, as shown in Figure 1.

Figure 3 is an end view of the machine. 35 Figure 4 shows in longitudinal sectional elevation a casing or cushion cover, as held, and a filler with certain adjacent machine elements including a ram for moving the filler into the casing.

Figures 5, 6, 7 and 8 show the means for 40 varying the distance of the travel of the ram for cushions of varying lengths.

Figure 9 shows a detail longitudinal section of means for varying the length of the telescopic piston rod for moving the ram, and

Figure 10 shows in longitudinal section a 50 means for locking the lateral, cushion-sizing elements against movement during the ramming operation.

Referring by numerals to the drawings, 55 11 designates a frame for the support of the table 12, whose top is plane and of dimensions approximating the maximum dimensions of cushions to be manufactured.

Coextensive in length with the table top and resting thereon in a manner to be moved laterally thereover are the two lateral sizing elements 13, which stand vertically from the table top forming a trough, or receiver 60 in which the filler is manually built, or made up.

At the forward end of the machine there are a fixed extension 14 of the table top and opposed lateral sizing element extensions 15 which will hereafter be termed the fixed casting holding means.

For the movements of the lateral sizing elements 13 and their extensions 15 I provide a cylinder 16, in which a fluid operated piston, having a rod 17, and whose operating medium is controlled by a valve 18 from a source 19, is connected with levers 20 arranged to rock, or oscillate, a pair of shafts 70 21 journaled in the frame 11 at each side thereof.

Secured to each shaft 21, to rock therewith is a lever 22, carrying at its upper extremity a pivoted link 23 which is coupled to 80 a lateral sizing element 13.

In order that the sizing elements may be held immovable, at times I provide locking means comprising friction clutch elements, one of which 24 is secured to the shaft 21 85 and another 25, provided with a threaded support 26 and a turning means or handle 27. (See Figure 10).

At the rear end of the machine, the frame 11 is extended above the plane of the table 90 12 for the support of a cross-shaft 28 upon which is journaled a beam 29, coextensive in length with the table top 12 and residing between the lateral sizing elements 13, and which beam has suspended therefrom the body portion 30 of the press, or vertical sizing element, which as shown has a length equaling the length of the table 12 and the fixed casing holding means.

For moving the press there is provided a cross-shaft 31 adjacent the front end of the machine which is pivotally connected with the beam 29 and which shaft extends at each end beyond the sides of the table top whereat are secured the piston rods 32, 32 of the cylinders 33, which latter elements are journaled as at 34, 34 to the machine frame and whose operating medium is controlled by a valve 35 from the source 19.

The press body 30 is associated with lateral sizing elements 36, 36, which are secured to the cross-shafts 28 and 31 whereby

they will be moved and held in parallelism with the press body 30 and each is provided with one or more hooks 37 whereby to "size" the press along with the lateral sizing elements 13.

To "set" the machine for repeated operations for cushions of uniform lateral dimensions I provide set collars 38, 38 on the shaft 28 and 31 which limit the movements of the lateral sizing elements in "sizing" directions, and which collars, obviously, may be set at different points along said shafts to provide for the sizing of cushions to different lateral or width dimensions.

By the provision of the extensions, of the trough or receiver elements, 14, 15, 15 and press elements 30, 36 and 36, beyond the table top and operating means a cushion casting, or cover, 39, (see Figure 4) may be readily placed over the sizing and press elements surrounding a built up "filler" in a position and condition to receive the "filler."

For moving the filler into the casing I provide a ram comprising a block 40, a cylinder 41 and a piston, having a rod 42, controlled by a valve 43 from the source 19.

To adapt the machine to size fillers of different lengths the piston rod 42 is made of a tube and an extension rod 44 is telescopically fitted therein and made adjustable by means such as the spring-dogs 45 (see Figure 9) and the relatively spaced slots, or openings 46, located respectively in the extension rod 44 and tubular piston rod 42.

By this means obviously the block 40 may be "set" in different positions for sizing cushion fillers of different lengths.

For convenience in releasing the dogs 45, I provide slip collars 47, carrying lugs 48 arranged to move and hold the dogs in planes beyond the openings 46.

For structural economy, I prefer to equip my machine with a cylinder of less length than the maximum cushion length and for this reason there is required means for readily changing the piston rod length. As illustrated in Figures 5 to 8, inclusive, I provide in addition to the recited spring-dogs 45 and openings 46, a block (40) holding means, comprising a stop 49, having a pivotal support 50, and arranged for projection through a hole 51, whereby it may be moved into or out of the path of the block 40.

By preference the stop actuating means comprises a push rod 52, and a spring 53 which tends to hold the stop in a position normally out of the path of the block 40.

By the expedient of the means, just recited, for operating the ram, a distance greater than the cylinder length, I am enabled to set up my machine in a relatively limited space and provide in the one machine ram movements greater than the cylinder length. Obviously the movement of the ram a distance greater than the cylinder

length requires more than one cylinder action or "push" and a resetting of the piston and its extension subsequent to each "push" or ram movement.

In the practical operation of the machine after the desired cushion dimensions are determined the filler sizing elements 13 are "set" for lateral sizing by moving them relatively to a spacing equalling the lateral or width dimension of the selected cushion dimension, then setting the collars 38, so that a subsequent movement of the elements 13, by means of the cylinder 16 and associated gear, comprising the levers 20, shaft 21, levers 22 and links 23 will not be beyond or less than the selected size.

This setting, by reason of the hooks 37, obviously "sets" the press, or vertical sizing elements, namely the elements 36, 36 to correspond with the elements 13, 13.

The machine is then set for longitudinal sizing by positioning the block 40 spaced from the extremity of the trough, or receiver, comprising the element 15, a distance corresponding with the selected length of cushion filler and setting the piston rod 42 and extension rod 44 by means of the spring-dogs 45 and slots 46.

With the sizing elements so set, the operator manipulates the valve 35 and through the cylinders 38, piston rods 32 and cross-shaft 31, the press, as a whole, including the beam 29, body 30 and adjustable sizing elements 36 are elevated, as shown by dotted lines in Figure 1, leaving the trough, or receiver, comprising the elements 13 "open."

With the press thus elevated and the receiver "open" the elements 13 of the receiver are moved, by a simple manipulation of the valve 18, to reside in positions relatively separated a distance greater than the lateral dimensions of the cushion filler to be made, or built up therebetween, so that ample space is allowed for such building up.

The operator then builds up a filler, between the two sizing elements 13 and between the block 40 and the extremity of the trough. After the filler has been built up, the valve 35 is again manipulated and the press brought to parallel the table thereby vertically sizing the filler. After thus vertically sizing the filler the operator manipulates the valve 18 and through the cylinder 16 and the recited gear associated therewith moves the lateral sizing elements including the elements 13, 13, 15, 15, 36 and 36 to their "limit" as determined by the set collars 38. At this time the cushion casing 39 is pulled or telescopically fitted over the projecting ends of the trough and press elements as shown in Figure 4 in a position to receive the filler.

With the cushion filler thus sized both laterally and vertically the sizing elements are locked against relative movements by

means of the described friction clutch so that the cushion filler will be held to its sized dimensions during its ramming from the machine.

5 The final step consists in bodily moving the filler into the casing which is accomplished by a simple manipulation of the valve 43 whereupon the block 40 or ram pushes the built up and properly sized filler into the 10 casing 39.

The finishing of the cushion then amounts to a mere closing of its one open end about the end of the filler.

It is my preference to employ compressed 15 air as the operating medium of my machine and in my drawings I have illustrated motors utilizing such motive fluid, but I in no sense wish to be understood as limiting myself to such operating means as is evidenced by the scope of my claims.

What I claim as new is:—

1. In an upholstering machine, a table, a vertical cushion sizing element, means for pivotally mounting one end of said element above the table, a valve controlled fluid actuated motor for raising and lowering the other end of the vertical sizing element, a pair of lateral cushion sizing elements, a valve controlled fluid actuated motor and 20 means for causing the motor to synchronously move the lateral sizing elements, adjustable means for limiting the movements of the lateral sizing elements in sizing directions, a ram, a valve controlled fluid actuated motor for the ram, means for locking 25 certain of the sizing elements during the action of the ram and extensions for said lateral and vertical sizing elements over which a cushion casing may be telescopically fitted 30 and through which the built up and sized cushion filler is forced to be received by the casing.

2. In an upholstering machine for forming cushions of different dimensions, comprising a table, width sizing elements associated therewith, means for moving said width sizing elements to predetermined positions on said table, a press for sizing the thickness of the cushions, means for moving 45 said press relative to the table, and a ram for sizing the lengths of the cushions comprising two relatively movable members and means for varying the relative position of 50 said movable members.

3. In an upholstering machine for forming cushions of different dimensions, a table, width sizing elements associated therewith, means for moving said elements to predetermined positions on said table, a press

for sizing the thickness of the cushions, 60 means for moving said press relative to the table, and a reciprocating plunger for sizing the length of the cushions having means associated therewith for varying its length.

4. In an upholstering machine for forming 65 cushions of different dimensions, means for sizing the width and thickness of the cushions to predetermined dimensions, and means for sizing the length of the cushions comprising a plunger and a fluid motor for 70 operating the plunger, the cylinder of the motor being shorter than the maximum cushion length, said plunger having means associated therewith whereby it may be lengthened to form cushions of maximum 75 length.

5. In an upholstering machine for forming 80 cushions of different dimensions, a table, means associated therewith for sizing the width and thickness of the cushions, and means for sizing the length of the cushions comprising a plunger and a fluid operated 85 motor therefor, the cylinder of said motor having a length less than the maximum cushion length, said plunger having means for varying its length, and stop means associated with said table for preventing the full return stroke of the plunger whereby one or more subsequent strokes of the plunger may size the cushion to the desired length. 90

6. In an upholstering machine, a table, a vertical sizing element, means for pivotally mounting one end of said element above the table, a valve controlled fluid actuated means for raising and lowering the other 95 end of said vertical sizing element, a pair of lateral sizing elements, a valve controlled fluid actuated motor and means to cause the motor to synchronously move the lateral sizing elements, a ram, and a valve controlled 100 fluid actuated motor for operating the ram.

7. In an upholstering machine, a table, a vertical sizing element, means for pivotally mounting one end of said element above the table, a valve controlled fluid actuated means 105 for raising and lowering the other end of said vertical sizing element, a pair of lateral sizing elements, a valve controlled fluid actuated motor and means for causing the motor to synchronously move the lateral sizing elements, a ram, a valve controlled fluid actuated motor for operating the ram, and means for locking certain of said sizing elements during the operation of the ram. 110

In testimony whereof I hereunto affix my 115 signature.

HOMER H. INGERSOLL.
